UNITED STATES PATENT OFFICE.

JACK WM. JAMES, OF MEMPHIS, TENNESSEE.

ORNAMENTAL CURB-BIT.

SPECIFICATION forming part of Letters Patent No. 478,868, dated July 12, 1892.

Application filed February 18, 1892. Serial No. 421,996. (No model.)

To all whom it may concern:

Be it known that I, JACK WM. JAMES, a citizen of the United States, residing at Memphis, in the county of Shelby and State of Tennessee, have invented new and useful Improvements in Ornamental Curb-Bits, of which the following is a specification.

This invention has for its object to provide a novel ornamental curb-bit; and it consists in the features of construction and the combination or arrangement of devices hereinafter described and claimed, reference being made to the accompanying drawings, in which—

15 Figure 1 is a perspective view of a curb-bit constructed in accordance with my invention. Fig. 2 is a detail plan view of the ornamental attachment for one of the cheek-pieces or side bars of the bit, and Fig. 3 is a detail perspective view of a driving-rein bit constructed according to my invention.

In order to enable those skilled in the art to make and use my invention, I will now describe the same in detail, referring to the 25 drawing Fig. 1, where the numerals 1 indicate the cheek-pieces or side bars, 2 the bit-bar or mouth-piece, and 3 the rein-rings of a curb-bit.

To render the bit handsome and attractive, 30 the cheek-pieces or side bars are each provided with an attached ornamental plate 4, formed tapering in the direction of its length to correspond with the tapered construction of the cheek-pieces or side bars. The edges 35 of the plates are formed integral with tongue-pieces 5, adapted to be clasped round the inner surfaces of the cheek-pieces for the purpose of securing the plates in position. The plates extend continuously along the cheek-pieces and terminate at or near the lower ends 40 thereof, and the exposed surfaces of the plates are ornamented with any desired design—such, for instance, as fox-hounds chasing a fox. The extremities of the cheek-pieces or 45 side bars, which extend above the mouth-piece or bit-bar for the attachment of the head-stall, are each provided with an ornamental plate 6, having tongue-pieces 7 at its edges, adapted to be clasped round the inner surfaces of such extensions in a manner 50 similar to the plates 4.

The rein-rings 3 are preferably mounted

loosely on cylindrical journals 8, depending from the lower ends of the cheek-pieces or side bars, and each rein-ring is covered on 55 its outer surface with a disk 9, having tongue-pieces 10 at its periphery to clasp round the opposite surface of the ring. The exposed surface of the disk is preferably ornamented in imitation of the dial-plate of a watch or 60 time-piece, and the plates 6 on the extensions of the cheek-pieces above the mouth-piece or bit-bar are ornamented with representations of horses; but I do not wish to be understood as confining myself to any particular ornamentation of the several attached plates, for 65 obviously various ornamental designs can be employed without altering the character of my invention.

The ornamental plates can be plated with 70 nickel, silver, or gold or other metal, and they serve to cover and protect the outer surfaces of the cheek-pieces and the rein-rings, while imparting thereto a very attractive appearance.

The ornamental plates can be stamped from thin sheets of the desired metal, and, as the tongue-pieces are integral therewith, they can be readily applied to any bits already in use. I do not, however, confine myself to the use 80 of the tongue-pieces for attaching the ornamental plates, as the latter can be otherwise attached.

In Fig. 3 I have exhibited an ordinary driving-rein bit having the rein-rings 12, provided 85 with ornamental disks 13, substantially as described with reference to Fig. 1, except that a different ornamentation of the disks is illustrated.

Having thus described my invention, what 90 I claim is—

1. An ornamental bit consisting of a bit-bar having rein-rings covered at their outer sides by ornamental disks, the edge portions of which extend round and are secured to the 95 rings, substantially as described.

2. An ornamental curb-bit consisting of a bit-bar having tapering cheek-pieces covered at their outer sides by tapering ornamented plates extending along the length of the tapering cheek-pieces and formed at the edges with tongue-pieces, which are clasped round the inner sides of the cheek-pieces, substantially as described.

3. An ornamental curb-bit consisting of a bit-bar and tapering cheek-pieces having rein-rings, said tapering cheek-pieces and rein-rings being covered at their outer sides by 5 ornamented plates formed at the edges with tongue-pieces, which are clasped round the cheek-pieces and the rein-rings, substantially as described.

In testimony whereof I have hereunto set my hand and affixed my seal in presence of 10 two subscribing witnesses.

JACK WM. JAMES. [L. S.]
